UNITED STATES PATENT OFFICE.

ISAAC SCHAFRAN, OF NEW YORK, N. Y., ASSIGNOR OF ONE-THIRD TO ARTHUR J. DUNKLE, OF NEW YORK, N. Y.

ELEVATOR FOR LIQUIDS.

Application filed August 6, 1927. Serial No. 211,070.

My invention relates to raising devices or elevators for liquids.

One of the objects of my invention is a new method of raising liquid from a lower level 5 to a higher level, in large quantities, by employment of an alternating succession of fundamental, physical functions, consisting of suction, confinement, displacement, and rotation of a liquid, thereby imparting there- 10 to centrifugal force.

Another object of my invention is to provide means for accomplishing the aforementioned successive operations.

The foregoing and further objects will be 15 come more fully apparent from the following description and the purely diagrammatical illustrations serving exclusively for the purpose of making the basic principle of my invention more easily perceivable.

Before describing my invention in detail, it will be advantageous to make clear the purpose for which my device is intended.

In places where irrigation is the only means of making the ground fertile, and particularly where the natural water supply is mostly located in canyons or valleys, normally inaccessible, and precluding the transportation of the required water to higher levels, expensive pump arrangements are used. Such 30 arrangements not only represent vast investments, but they are also costly in operation, and usually most inadequate, due to their inherent limitations and the result obtainable by them.

In order to raise water in adequate quantities at the least expenditure of money, which latter factor is essential for practicable cultivation of land, a simple, and comparatively inexpensive device is required, capable of accomplishing the required results economically.

My new device is designed to fill these requirements. It is based on purely physical functions and properties of liquids, and on 45 physical force imparted thereto.

I may enumerate those functions successively occurring during the operation as follows:

First, suction, created by lifting an 50 immersed body, thereby attracting liquid into the place vacated by the lifted body.

Second, confinement of the liquid in a vessel, which consists in preventing the sucked-in liquid from leaving its place.

Third, displacement, and subsequent rais-

ing of the liquid by submerging a solid body into the liquid.

Fourth, imparting a rotary motion to the liquid, thereby creating centrifugal force, which results in the tendency of the liquid 60 to rise at the edge of the vessel in which it is confined.

Fifth, increasing the centrifugal force imparted to the liquid, by gradually increasing the diametrical dimensions of the liquid body 65 through the agency of a conical vessel wherein the liquid is confined.

The foregoing are some of the high points upon which my invention is based. These and other essential functions will be more 70 readily understood in connection with the drawings.

Figure 1 is a diagrammatical form, partially in cross section, of my device,

Figure 2 is a cross sectional view, taken on 75 line 2—2 of Figure 1,

Figure 3 illustrates a perspective view of a single liquid elevating device and,

Figure 4 illustrates the principle of a battery of liquid elevating devices. 80

In the drawings, numeral 10 denotes a body of water in which is partially submerged a vessel 11, which is preferably of an inverted conical shape, the lower end of which terminates in a cylindrical base 12.

The outer body of water communicates with the interior of the vessel by means of apertures 13, preferably equipped with valves 14. The latter are so arranged as to permit the inrush of water until the water inside 90 reaches the level of the outer body of water, when valves 14 automatically close so as to confine the water within the vessel.

At the upper end of the cylindrical base portion of the vessel, there is provided a 95 wave-shaped run-way 15 for a plurality of rollers 16, attached to a semi-floating body 17. The latter is adapted to rotate, and while rotating, to reciprocate in up and downward directions. The shape of body 17 is preferably that of an inverted frustum pyramid, terminating at its lower end in a cylindrical extension 18. From the latter project outwardly, arms 19, adapted to engage and close valves 14 when body 17 descends. 100

At the upper end of vessel 11, there is provided an enlargement 20 and a spill-way 21. Mounted on the enlargement 20 there is a frame 22, adapted to support a coupling 23, provided for the purpose of permitting cur- 110

rent to be fed into the body 17, through cables 24 and 25, while the body rotates and alternately descends and ascends. At the upper edge of body 17 there are provided spacing 5 means 26, adapted to prevent contact of the upper edge of the body with the vessel.

Projecting from the sides of body 17, is a plurality of propellers 27, the shafts of which are inclined upwardly, and at an angle relative to the body sides, as clearly seen in Figures 1 and 2, respectively. Each of the propellers are driven by motors mounted within body 17 and fed by the main cable 25.

Operation.

When current is supplied, the motors driving the propellers are set in motion. The lower row of propellers submerged in the water within the vessel, will commence to 20 impart a rotary motion to the body 17. During each quarter turn of the body, the latter descends and ascends in succession. While descending, it depresses the water held within the vessel by the now closed valves 14, 25 thereby causing the water to rise successively until it reaches the second line of propellers.

Due to the fact that the propellers are inclined upwardly, the water is so-to-speak, pushed upwards due to the reaction, caused by 30 the propellers. The successive up and down motion of the body causes intake of water and rise of its level, which continues until the top rim of the vessel is reached. In addition to the up and down motion of the body, 35 which acts in the same manner as would a plunger, the rotary motion of the body imparts a rotary motion to the water, which function in turn, results into imparting centrifugal force to the water.

40 Due to the fact that the vessel is of an inverted cone-shape, the centrifugal force of the water increases as it reaches greater diametrical dimensions. The centrifugal force in itself will have the tendency to push the 45 water upwards and, combined with the other functions caused by body 17, will enhance the effectiveness of raising the water from its original level to a higher level.

It is obvious that there will be limits as 50 to the height of my device, and that there might necessarily arise problems where the lifting of the water will have to be accomplished in stages, in the way illustrated in Figure 4, where two or more elevators for 55 liquids are employed.

As has been said before, the drawings by no means illustrate the final construction of my device, and merely serve for explaining the principle of my new method of raising 60 liquid from lower to higher levels.

Be it understood therefore that I shall not be limited to whatever showing is made in the drawings, and that I reserve for myself the right to make such improvements 65 or changes within the broad scope of my in-

vention, based on the principles of the process involved.

I claim:

1. A device for raising liquid from lower to higher levels, comprising a vessel capable of alternately receiving and retaining quantities of liquid, a floating, revoluble, body within said vessel, adapted alternately to ascend and descend, while revolving, thereby causing an alternate intake and rise of, 70 and simultaneously imparting a centrifugal motion to the liquid within said vessel and means associated with said body for imparting thereto the aforesaid motions.

2. A device for raising liquid from lower 80 to higher levels, comprising a vessel, adapted to be partially submerged in and alternately communicating with a body of liquid and capable of alternately receiving and retaining a given quantity thereof, a semi-floating, 85 revoluble, member disposed within said vessel and adapted to alternately ascend and descend while revolving, thereby causing, respectively, a suction of liquid into said vessel, and retention and rise thereof, due to 90 displacement, while at the same time imparting centrifugal motion to the liquid within the vessel and means associated with said member for imparting thereto the aforesaid motions.

3. A device for elevating liquid, comprising a vessel, a semi-floating revoluble reciprocating member therein, and means for facilitating, alternately, an intake and retention of liquid in said vessel.

4. A device for elevating liquid, comprising a substantially conical vessel, a substantially conical, revoluble and reciprocating member within the vessel, and means for facilitating, alternately, an intake and retention of liquid within said vessel, the former brought about by the upward movement of said member, while its downward movement causes a rise of the liquid to a higher level.

5. A device for elevating liquid, comprising an inverted, substantially conical vessel, an inverted, substantially pyramid-shaped semi-floating member therein, capable of rotary and reciprocating motions, means associated with said vessel for facilitating intake of liquid when said member, while revolving, moves upwards, and retention of liquid, when said member, while revolving, moves downwards, thus alternately causing suction and rise of the liquid within the vessel, while imparting to the liquid a rotary motion, resulting into centrifugal force, which increase as the mass of liquid reaches higher levels and larger diametrical dimensions.

6. The process of elevating liquid from lower to higher levels, which consists, of successively causing suction, confinement and rise, by displacement, of liquid, while imparting thereto a rotary motion, by revolving in said liquid a reciprocating semi-floating body.

7. The process of elevating liquid, which consists, of alternately and successively causing suction, confinement and rise, by displacement, of liquid, while imparting thereto a rotary motion and centrifugal forces, by revolving in said liquid a semi-floating body and causing the latter to alternately ascend and descend, while revolving.

8. The process of elevating liquid, which 10 consists, of alternately and successively causing suction, confinement and rise, by displacement, of liquid, while imparting thereto

a rotary motion, by revolving in said liquid a body and causing the latter to alternately ascend and descend, while revolving, and 15 simultaneously increasing the dimensional properties of the liquid, proportionately with each rise or displacement period, thus enhancing the centrifugal force of the revolving liquid. 20

Signed at New York, in the county of New York and State of New York, this 29th day of July, A. D. 1927.

ISAAC SCHAFRAN.
